METHOD AND APPARATUS FOR HOMOGENIZING POWDERED MIXTURES

Edouard Hastert, Esch-Alzette, Luxemburg, assignor to Louis Peters, Duesseldorf, Germany

Application July 9, 1935, Serial No. 30,574
In Germany October 24, 1934

3 Claims. (Cl. 259—99)

According to this invention the air under pressure used for homogenizing powdered or pulverulent masses has to accomplish two different functions. First this air produces in the powdered mass transport currents of variable localisation and secondly this air has to drive into these currents powdered mass taken from around it.

The invention thus provides for introducing the amount of air in conditions of delivery, pressure and emplacement such as to produce in the powdered mass distinct currents taking along the whole of their travel material from the surrounding mass, and this with an impulse sufficient for going through the whole width of the mass.

The invention also provides for producing the incorporation of part of the surrounding mass in the transport currents by continually varying the impulse imparted to these currents.

20 And also the invention provides for varying this impulsion of the air under pressure in the mass to be treated.

The accompanying drawing shows by way of example, and in a non-limitating manner, a device for carrying out the invention.

25 In the drawing: Figure 1 is a longitudinal vertical section; Figure 2 is in its left part a section along IIa—IIa of Figure 1 and in its right part a section along IIb—IIb of Figure 1.

30 In the bottom of the receptacle or container M air ducts such as T are provided, the number, form and disposition of which being determined for each particular case. These ducts are provided with apertures of small section for the introduction of air in the mass to be treated. 35 Each of these ducts is connected to the air supply header B by a valve chamber S. The different valves are actuated by a cam-shaft A common to all the valves. The form of the cams and their arrangement on the shaft A determine the order 40 of air admission in each duct, the relative duration of each admission and the amount of impulsion, which last is in relation with the degree

of maximum aperture of the different valves. The rotational speed of the shaft A determines the frequency of the variations of impulsion of the different transport currents. The speed, by acting on the effective duration of each impulse, 5 also acts on its amplitude, that is, on the extent of its influence zone.

For preventing matter in treatment penetrating the air ducts, the invention provides for establishing between the delivery of air under 10 pressure and the speed of rotation of the shaft A such a relation that the impulse imparted to the matter in the proximity of the air introduction apertures be sufficient to maintain it away 15 from these apertures.

When the container has been filled with powdered mass, air is admitted in the header B and the shaft A is put in rotation.

When the matter is homogenized, it is taken 20 out of the container by the discharge opening V, the action of air under pressure being maintained until the container is wholly empty.

What I claim is:

1. A process for homogenizing pulverulent material, consisting in injecting currents of air of 25 varied speed into non-contiguous locations of the material to be treated.

2. A process for homogenizing pulverulent material, consisting in injecting a plurality of currents of air into non-contiguous locations of the 30 material to be treated, and varying the locations of injection of said currents of air.

3. Apparatus of the character described, comprising a vessel for holding material to be homogenized, means for supplying compressed air as 35 sociated with the base of said vessel, conduits for feeding air under pressure from said supply means to regions within said vessel adjacent the base thereof, and means for controlling the periodic admission of compressed air to said 40 conduits.

EDOUARD HASTERT.
